UNITED STATES PATENT OFFICE.

WILLIAM A. BERNARD, OF NEW YORK, N. Y., ASSIGNOR TO BERNARD,
WALKER & RICE, OF SAME PLACE.

PUNCH.

SPECIFICATION forming part of Letters Patent No. 427,497, dated May 6, 1890.

Application filed October 18, 1889. Serial No. 327,429. (No model.)

To all whom it may concern:

Be it known that I, WILLIAM A. BERNARD, a citizen of the United States, residing in the city and State of New York, have invented 5 an Improvement in Combined Pliers and Punches, of which the following is a specification.

This tool is especially adapted to leather-workers and for lacing belts, also to bookbinders and jewelers and workers in sheet metal.

I make use of parallel jaws adapted to grasping the belt, leather, or other article, and I combine with such pliers a movable punch 15 having a parallel motion and die held by an arm extending up from one of the jaws, and there is a gage between the jaw and the arm to regulate the distance from the edge of the belt or leather where the punch is made to 20 perforate, so that in this one tool is combined pliers, the punch, and the gage, and the punch is removable so that a punch of different size can be inserted, or the punch can be removed, if desired, for rendering the pliers 25 more convenient in use.

In the drawings, Figure 1 is an elevation, and Fig. 2 is an end view, of the tool; and Fig. 3 is a section longitudinally through the jaws and arms.

30 The jaws A B are received between the cross-pieces of the sheet-metal-handle levers, in which C C are the handle portions, and D D the cross-pieces formed of the sheet metal and crossing each other in pairs and riveted together at 2, to form the pivots for the handle-levers, and at 3 are rivets or screws passing through the forward ends of the cross-pieces and through the jaws and forming the forward fulcrum connecting the jaws A B 35 with the handle-levers, and the rivets or screws 4 pass through the handle-levers and through slots in the rear portions of the jaws A B, and the distance between the pivots 2 and rivets or screws 3 and 4 is the same, or 40 nearly so, in order that a parallel movement may be given to the jaws A B as the levers C C are open or closed.

In one jaw A there is a longitudinal hole, into which is received a contractile helical 45 spring E, one end of which is made as an eye for one of the screws or rivets 4 to pass

through, and there is a hook or eye at the other end of such spring for a pin 5 to pass through. This spring E is distended as the jaws are closed together, and by its contraction the jaws are opened, and it will be apparent that this spring, being within the jaw A, is protected from injury, and is a reliable device for opening the pliers after they have been pressed together in use. 60

Upon the jaw B, and formed therewith or permanently attached thereto, is the arm F, extending along and at the back of the jaw and parallel thereto and at a sufficient distance therefrom for the insertion of the leather 65 or belt or other article through which the hole is to be punched, and at the outer end of this arm F is the removable die or counter 6, and through the jaws A B are transverse holes for the reception of the punch G, which punch 70 has head 8, a screw-shank at 9, and a cutting end 10, and the points of this cutting end are adapted to the hole or recess in the removable die or counter 6. The diameter of the screw-shank 9 is to be as great as the largest-sized 75 hole to be punched by the tool, and the hole in the jaw B corresponds in size to the plain part of the shank 9, so that such shank is guided by the jaw B, and the screw upon the shank allows for the punch being removed 80 when not required for use and for the insertion of another punch of the desired size and character, and in consequence of the jaws A and B opening and closing parallel the movement of the punch is in a straight line, 85 and it is guided with certainty by the jaw B to the movable die or counter 6, and I remark that this movable die or counter 6 is screwed or otherwise secured into the hole at the end of the arm F, so that such die or counter is 90 changed from time to time as the punch may be changed.

For perforating leather or rubber belts or similar articles, I prefer to make the cutting end 10 of the punch with two projecting points 95 between a semicircular or nearly semicircular groove cut across the end of the punch, so that these points penetrate the leather or similar material and commence to cut gradually, and they remove the piece of material by pressing 100 it through the hole in the counter-die 6. If the punch is to be adapted to the insertion

of eyelets, the end of the punch and the surface of the counter-die are to be formed in the usual manner for pressing up such eyelets after they have been inserted through 5 the belt or other article receiving the same, and it will be apparent that if the punch G is unscrewed and removed from the jaws there is an unobstructed opening through 10 between the jaws from end to end adapted to the passage of a rod, strip, or piece of material of any desired length, and the jaws, moving parallel to each other, can be pressed upon and hold firmly any such rod or strip.

I prefer to employ a gage H of a size 15 adapted to pass in between the back of the jaw A and the inner side of the arm F, and to this gage a bar 12 is connected, and it passes back through a hole in the base of the arm F, adjacent to and in line with the back 20 of the jaw B, so that the end of this bar 12 may be within the hollow portion of the sheet-metal handle, and there is a clamping-screw 13, for holding the bar 12 and gage H in position when adjusted. This gage H serves to 25 determine the distance from the edge of the belt or other article at which the punch G perforates such article.

This tool is very convenient for perforating the ends of leather or of belts for the 30 reception of the lacing. It is to be understood that the sheet-metal handles are pressed up within dies and the metal is to be of sufficient thickness to furnish the required strength, and usually such sheet metal will be steel, 35 and it can be pressed up to shape in either a hot or cold condition, the blank having previously been cut out by dies, and there is very little hand-work in manufacturing this improved tool.

40 It will be seen that the punch is sufficiently near the fulcrum of the handle-levers for obtaining the power necessary for actuating the same, and that in consequence of the arm being upon one of the jaws and running back behind the fulcrum the holes in the 45 belt, sheet of metal, or other article can be at a greater distance from the edge than the distance from the fulcrum to the punch. This is a great convenience, because in most hand-punches heretofore made the holes cannot be 50 punched at a greater distance from the edge than the distance from the punch to the fulcrum.

A hollow punch can be used in the same 55 way as a solid punch, and the head 8 of the punch can be used as a hammer, if desired, and for sheet metal and similar material the punch should have a flat end.

I claim as my invention—

60 1. The combination, with the sheet-metal-handle levers having cross-pieces united to-

gether at 2, of the jaws A B, the rivets or screws 3 and 4 passing through the sheet-metal lever-handles and through the jaws, such jaws being slotted for the rivets or 65 screws 4, and the spring E within the longitudinal hole in one of the jaws and serving to open such jaws, substantially as set forth.

2. The combination, with the lever-handles having cross-pieces riveted together, of the 70 jaws A B and the rivets or screws connecting the same to the lever-handles, the jaw B, having an arm F formed with or connected to it and extending along the back of the jaw, and a punch G, passing transversely through 75 the parallel-moving jaws and a counter-die in the end of the arm, against which the punch acts, substantially as set forth.

3. The jaw B and its arm F, in combination with the jaw A, the handle-levers having 80 cross-pieces pivoted together at each side of the jaws and pivoted to the jaws, so that the jaws move parallel, the punch G, removably connected to the jaw A and passing through and guided by the parallel-moving jaw B, 85 and acting against the counter-die at the end of the arm F, substantially as set forth.

4. The combination, with the parallel-moving jaws A B and arm F, permanently connected with the jaw B, of the lever-handles 90 and connecting rivets or screws for giving to the jaws a parallel movement, the removable punch G, screwed into the jaw A and passing through and guided by the jaw B, and a gage H between the arm F and the jaw B, substantially as set forth.

5. The combination, with the lever-handles having cross-pieces pivoted together, of the parallel-moving jaws A B and the connecting rivets or screws, the arm F, formed with or 100 permanently connected to the jaw B, the gage H, and bar 12, the latter passing through the hole in the base of the arm and extending within the hollow portion of the lever-handles, and a screw 13 for clamping the bar 105 and gage, substantially as set forth.

6. The parallel-moving jaws A B and arm F, formed with or permanently connected to one of the jaws, a removable punch G, passing transversely through the parallel-moving 110 jaws and screwed into one jaw and guided by the other jaw, substantially as set forth, and the lever-handles pivoted together and to the parallel-moving jaws, and also giving motion to the jaws and punch, substantially as set forth.

Signed by me this 14th day of October, 1889.

WILLIAM A. BERNARD.
